UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed January 21, 1924. Serial No. 687,433.

This invention relates to improvements in antifriction bearings.

The object of this invention is to provide an antifriction bearing especially adapted 5 for use as a side bearing for railway cars and more specifically, the object of the invention is to provide new and improved means for insuring the return of the anti-friction element to normal position after 10 each actuation of the bearing.

In the drawing forming a part of this specification, Figure 1 is a vertical sectional view taken through portions of the body and truck bolsters of a railway car, showing my 15 improvements applied thereto. And Figure 2 is a vertical, sectional view taken substantially on the line 2—2 of Figure 1.

In said drawing, 10 denotes the under side 20 of the body bolster and 11 the upper side of the opposed truck bolster of a railway car. As shown, my improved side bearing is applied to the truck bolster and the same comprises broadly, a retaining member, housing or base casting A; an anti-friction element 25 B; and a pair of side weights or pendulums C—C.

The base casting A is of box-like form, the same having curved end walls 12 and side 30 walls 13, the latter being extended transversely inwardly on opposite sides of its vertical center line to form inwardly extending flanges 14, these flanges thence extending upwardly at 15 to the top of the casting. Vertically extending guideways or recesses 16 are formed centrally of the side walls of the casting, these recesses having parallel vertical walls and opening into the interior of the casting, and being preferably under-cut 35 or outwardly flared at their lower ends, as indicated at 25. Legs 17 are formed on the bottom of said casting and extend transversely thereof for attachment to a wear plate or bearing plate 19 by means of rivets 18. The wear plate is in turn mounted upon 40 the truck bolster by rivets 20.

The anti-friction element B is in the form 45 of a cylindrical roller adapted to roll back and forth to either side of its normal central position on the bearing plate 19 and to project upwardly beyond the top of the base casting for bearing engagement with the under surface of the body bolster 10.

The side weights or pendulum members 50 C—C are arranged at the ends of the anti-friction element, each of said pendulums

having a heavy enlarged lower portion 21, a narrow rod-like relatively light weight upward extension 22 integral therewith and rigidly extending radially therefrom, and a substantially cylindrical pin portion 23 at 60 the upper end of said extension 22 transversely thereof. The pendulums C—C are pivotally mounted at the top of their enlarged portions, on the projecting ends of a pin 24 extending axially through the anti-friction roller, and the portions 23 of the pendulum members are adapted to pivotally and slidably engage in the vertical recesses or slots 16 of the base casting. Thus, the major portion of the weight of the counter- 65 balance members lies below their pivotal axes, as shown in the figures of the drawing, so as to most efficiently perform their counter-balancing function.

In assembling the parts, the anti-friction 70 element, together with the pendulums pivoted thereto is inserted into the base casting from its bottom, and the wear plate 19 is then riveted in place to the casting so as to prevent any loss of parts either in transit or 75 after they are in place on the bolster.

The normal position of the parts is as shown in full lines in Figure 1. In operation, assuming that the body bolster moves to the left relatively to the truck bolster, the anti-friction roller will be shifted toward the position shown in dotted lines in Figure 80 1, carrying the pendulum members therewith and causing them to be oscillated about their respective pivots 24 in such manner 85 that they will assume the position of unstable equilibrium shown in dotted lines in Figure 1. As soon as the pressure is released, the pendulum members will tend to return to their normal position indicated in 90 full lines, thus bringing the roller back to its normal central position. During the return action, it is evident that the members C—C fulcrum about their upper ends 23—23 95 so that the load from the members C—C is 100 applied to the roller B at 24 with a multiplied average effect. By undercutting the lower ends of the guiding slots 16, it is possible for the enlarged portions 21 of the pendulum members to assume a higher elevation at the extreme position of the roller 105 than if such portions were not under-cut, and yet at the same time permit of the upwardly extending portions of the pendulums, beyond the pivotal points, being as 110

small or light in weight as possible. The flanges 14 act as stops to limit the lifting of the roller relative to the casting. Axial shifting of the roller is limited by the pendulums engaging the housing walls, and the coacting guideways and pendulum extensions practically prevent a too free rolling of the anti-friction element when free from load.

10 I have herein shown and described what I now consider the preferred manner of carrying out my invention but the same is merely illustrative and I contemplate all changes and modifications that come within 15 the scope of the claims appended hereto.

I claim:

1. In an anti-friction bearing, the combination with a housing having a bearing surface therein and alined vertical guideways 20 at its sides; of an anti-friction roller within said housing, adapted to roll back and forth on said bearing surface, said roller having a pin projecting axially from its ends; and pendulum members arranged between the 25 ends of said roller and the corresponding sides of said housing, each pendulum member comprising a heavy enlarged lower portion pivoted at its upper end to said pin and also having a relatively light rod-like portion rigidly therewith, the latter being provided with a transversely extending rounded lug at its upper end, said lugs slidably and 30 pivotally engaging in the vertical guideways of said housing, whereby said roller will 35 oscillate the enlarged portions of said pendulums to cause the same to be displaced relatively with reference to the central vertical axis of said roller and in advance thereof to positions of unstable equilibrium 40 when actuated, to return said roller to its normal position when the actuating pressure is released.

2. In an anti-friction bearing, the combination with a retaining member adapted to 45 be mounted on a truck bolster and having

vertical guideways at its sides; of an anti-friction roller adapted to roll back and forth in said retaining member; and pendulum members arranged between the sides of said retaining member and the corresponding ends of said anti-friction roller, each pendulum member comprising a substantially heavy portion pivotally connected at its top to the axis of said roller; a relatively light-weight upwardly directed extension rigidly and integrally connected to said heavy lower portion, the upper end of said extension being provided with a transversely extending lug, said lug being limited to slidably and pivotally move in said vertical guideways of the housing when said roller moves to either side of normal central position to oscillate the pendulums about their pivotal axes, the lower ends of said guideways being under-cut to permit full movement of said pendulums, the pendulums returning said roller to its normal position when the actuating pressure on the roller is released.

3. In an anti-friction bearing, the combination with a support having an extended bearing surface; of a roller having movement on said support lengthwise of the latter; an arm pivotally mounted between its ends on the roller for swinging movement on 70 an axis concentric with the axis of the roller, said arm being weighted at one end, said weighted end being free to swing; means for guiding the end of the lever remote from the weighted portion in a path at an angle 75 to the direction of movement of the roller to effect movement of said weighted end of the lever away from the normal dead center position thereof at a constantly increasing 80 accelerated speed with respect to the speed of movement of the roller.

In witness that I claim the foregoing I have hereunto subscribed my name this 16th day of January 1924.

JOHN F. O'CONNOR.
